RAILWAY BUFFER

Raymond P. Delano, Jr., Wilmington, Del., assignor to
Franklin Balmar Corporation, a corporation of Delaware

Application August 30, 1954, Serial No. 453,055

10 Claims. (Cl. 213—15)

This invention relates to buffer mechanisms for railway vehicles and is particularly concerned with novel buffer mechanisms for transferring buffering forces between adjacent vehicles without developing excessive lateral forces.

The problem of the transmission of buffering forces between railway vehicles, incident to pushing and particularly to braking operations, has been aggravated by increasing train weights and locomotive tractive effort and particularly by the employment of dynamic braking in electric or electric-drive locomotives.

Modern locomotive units may develop steady-state braking forces of the order of 40,000 to 50,000 lbs. and when such units are combined into multiple unit locomotives, the total braking force developed may be as high as 150,000 lbs.

Conventionally, buffering forces are transmitted from one unit to another through fixed points on the vehicle center line near the ends thereof—for example, through the draft gear and coupler pins. The coupler pins are located near the ends of the vehicle frame, and, in locomotive units, relatively remote from the truck center pins. When one or more of the vehicles is on curved track, the line connecting the coupler pins of two adjacent units has its axis displaced from the longitudinal axis of one or both of the units. As a result, the compressive force between the coupling pins has a component normal to the axis of one or both of the adjacent vehicles, whose magnitude is a function of the buffering force, the draft gear length, the distance between the coupler pin and the truck pin, and the misalignment between the vehicles. In a typical diesel-electric locomotive unit developing a braking force of 46,000 lbs. the lateral component of the steady-state force, in buff, may be as high as 15,000 lbs. on a 21° curve.

Lateral forces of this magnitude are sufficient in some cases to cause derailment, and in any case, promote flange and rail wear, and tend to establish a jackknifed condition of the two units, which condition may be maintained even after the two vehicles pass from a curve on to tangent track.

In the past, draft gear centering devices have been employed to restore the vehicles to aligned condition once they reach tangent track, but since such devices develop lateral forces of the order of 300 to 400 lbs. at most, they are ineffective to prevent the establishment of the jack-knifed condition in the first place. Furthermore, draft gear or coupler centering devices increase the difficulty of coupling vehicles when one or more of them is on curved track.

According to the present invention, buffering forces are transmitted from one vehicle to an adjacent vehicle through buffer mechanism which is arranged to transmit the buffering force along a line (for example, the line connecting the truck pins of the adjacent vehicles) selected to eliminate or at least radically decrease the lateral component of the buffering force as compared to that inevitably

2

developed when the buffering force is transmitted through conventional means.

According to this aspect of the invention, the buffer mechanism is arranged to transmit the buffering force along 5 the line passing through or near the truck center pins in any relative angular position of the two vehicles.

Thus, the point at the end of one vehicle through which the buffering force is transferred to the adjacent vehicle shifts transversely of the vehicle with changes in the relative 10 positions of the two vehicles.

Desirably, the point of transfer shifts continuously with changes in relative angular positions of the two vehicles, along an arc whose center is at or near the adjacent truck center pin.

15 In addition to the steady-state forces developed by locomotive braking or pushing operations, large amounts of potential energy in the form of momentum are frequently released in the form of buffering forces of high peak magnitude incident to acceleration, deceleration, coupling operations and the like. The peak magnitudes of such forces far exceed the magnitude of steady-state forces above discussed, and any buffer mechanism must be constructed to accommodate them.

In accordance with another aspect of the invention, the 25 buffer mechanism incorporates resilient and/or friction means designed to absorb instantaneous or transient buffering energies of large peak magnitude.

Desirably, according to this aspect of the invention, the 30 mechanism incorporates a buffer spring in helical form arranged with its axis transverse the longitudinal axis of the vehicle, together with friction wedge means arranged to dissipate a portion of the energy of the buffering transient, as heat.

It is a primary object of the invention to transmit buffering 35 forces from a vehicle to an adjacent vehicle in a manner to avoid the development of lateral forces tending to misalign the vehicles.

It is a further primary object of the invention to reduce the peak magnitude of buffering transients either by temporary 40 displacement of resilient means or by dissipating a portion of the energy of the transient through friction means, or both.

It is a further object of the invention to accomplish the first two mentioned objects by one buffering assembly.

45 Another object of the invention is to provide a buffer mechanism which can be accommodated in a minimum of space in the structure of the vehicle.

A further object of the invention is to provide a buffer 50 mechanism adapted to simple assembly with standard diaphragm mechanisms and other portions of existing vehicles.

Still another object of the invention is to accomplish one or more of the foregoing objects in a manner which largely or wholly divorces the buffering action from the drawgear of the vehicle; and in this regard the invention further contemplates transmitting the draft forces, from vehicle to vehicle, between points which are relatively closely spaced apart (thus avoiding excessive draw gear length), while transmitting buffering forces, from vehicle to vehicle, between points which are relatively widely spaced apart, preferably between points at or near the truck centers of adjacent vehicles (thus avoiding excessive lateral forces, in buff).

55 65 How the foregoing and other objects of the invention are attained will be more clearly understood from the description which follows and from the drawings, in which—

Figures 1 and 2 diagrammatically illustrate and compare the lateral forces on locomotive units employing the invention (Figure 2) and similar units following the prior art (Figure 1), the first unit in each figure being on a

curved run of track and the second unit (and third, not shown) being on a straight run of track;

Figures 3 and 4 are diagrams similar to Figures 1 and 2, but with the first two units on a curved run of track and the third unit on a straight run of track. Figure 3 represents the operation of the prior art arrangement and Figure 4 that of the buffer mechanism of the invention;

Figure 5 is a diagrammatic view illustrating the action of buffers embodying the invention in which the buffing-force transfer-point shifts continuously, with the left hand unit on a straight run of track and the right hand unit on a curved run of track;

Figure 6 is a view similar to Figure 5 with both units on curved track;

Figure 7 is a plan view, partly in section, of a form of buffer mechanism which functions in accordance with Figures 5 and 6;

Figure 8 is a cross sectional view taken on the line 8—8 of Figure 7;

Figure 9 is a plan view, partly in section, of a modification of the buffer of Figures 7 and 8 with certain of the associated structure shown in dot-and-dash lines;

Figure 10 is a face view, partly in elevation and partly in section, of the buffer mechanism of Figure 9, taken substantially on the line 10—10 of Figure 9;

Figure 11 is a side elevation of the buffer of Figures 9 and 10 with associated mechanism shown in dot-and-dash lines;

Figure 12 is a cross sectional view taken on the line 12—12 of Figure 9; and

Figure 13 is a chart illustrating the relationship between relative buffing motion and resistance to buffing in a locomotive comprising two units equipped with conventional draft gear and also with the buffer mechanism of the invention.

In Figures 1 to 4, I have diagrammatically indicated the lateral forces developed during buffing. The diagrams are based on a three-unit locomotive, each unit of which is provided with two trucks with their center pins 372 inches apart, with the draft gear coupling pins spaced 122½ inches from the truck center pins, and with a draw bar length of 57 inches (28½" from pulling face to coupling pin center, in the case of knuckle-type couplers).

In all of the diagrams, the lateral forces are expressed numerically in terms of the quantity B, which as indicated in the drawings, is equal to the braking force developed by one unit, although it is to be understood that the diagrams are applicable to cases wherein the buffing force is developed by pushing or otherwise. The magnitude and direction of the lateral forces acting on the truck centers are also indicated graphically by the length and direction of the arrows "L."

Figure 1 illustrates the lateral forces developed on the trucks of the first and second units when the buffing force is transferred from unit to unit between fixed points located on the center line near the ends of the units, for example, through the draft gear and couplers. When the leading unit is on a curve and the second and third units are on tangent track (the situation illustrated in Figures 1 and 2), the trailing end of the leading unit swings to the outside of the track center line, and the two vehicles assume a jack-knifed position with respect to one another. The compressive force in the draw bar or coupler intersects, at considerable angles, the longitudinal center lines of the vehicles, as a consequence of which it has a lateral component urging the trailing end of unit No. 1 toward the outside of the curve and the leading end of unit No. 2 toward the inside of the curve. The magnitude (in terms of "B") and direction of the forces on the trucks of the two units are indicated by the arrows "L" (with suffixes hereinafter referred to). As may be seen, the lateral force L₁ on the trailing truck of the leading unit is equal to .2227B. Since "B" may be equal to more than 40,000 lbs., the lateral force on this truck may be as much as 9500 lbs.

Figure 3 illustrates the forces developed in a similar locomotive when both unit No. 1 and unit No. 2 are on curved track and unit No. 3 is on tangent track. In this situation, the draw bar between the unit No. 1 and unit

5 No. 2 is displaced outwardly of the center line of the track. The buffing force which must be transferred between unit No. 2 and unit No. 3 is 2B and the lateral component L₃ of this force on the trailing truck of unit No. 2 is .4244B, or, in the example mentioned, upwards of 10 16,000 lbs. It will be noted that the force L₄ on the leading truck of unit No. 2 is lower than in the situation illustrated in Figure 1, because the two lateral forces acting on the two ends of unit No. 2 oppose one another insofar as rotation of unit No. 2 about its center is concerned.

15 Several conclusions can be drawn from the diagrams of Figures 1 and 3, among them that the lateral forces increase with the braking force and with the number of units, that the greatest lateral forces are developed when one unit is on tangent track and the adjacent one is on 20 curved track, and finally, that the magnitude of the lateral force is a function of the angle at which the buffing force transmitted from one vehicle to another intersects the longitudinal axes of the vehicles. In addition it will be noted that even when adjacent vehicles are on tracks 25 curving in the same direction, the forces developed will (under some conditions) urge the ends of the vehicles in opposite directions.

According to the invention, the buffing force is transmitted from vehicle to vehicle along a line which is selected with a view to developing the minimum possible lateral force. Desirably, the line selected is the line connecting the truck centers, and the operation of a system embodying buffing-force transfer-points lying on the line of truck centers is illustrated in Figures 2 and 4. In 35 Figure 2, for example, I have diagrammatically indicated the lateral forces developed when the buffing force is transmitted between the first and second units by means of buffing surfaces of arcuate form centered on the truck centers.

40 In Figure 2, it is assumed that there is sufficient lost motion in the draw bar so that no buffing force is transmitted through the draft gear and that the entire force is transmitted along the line C. It will be noted that in Figure 2, the lateral force L₅ on the trailing truck of unit No. 1 is about one-fourth of that of the force L₁ in Figure 1, and that the force L₆ on the leading truck of unit No. 2 in Figure 2 has been reduced to a negligible quantity compared with the corresponding force L₇ in Figure 1.

50 Similarly, in Figure 4, in which the buffing forces are also transmitted from vehicle to vehicle along lines connecting the truck centers, the lateral forces have been drastically reduced, so that the lateral force L₈ (that on the trailing truck of unit No. 2) has been reduced to a small fraction (about one-twelfth) of the force L₃ developed in the conventional mechanism illustrated in Figure 3. And it will be noted that in the mechanism of Figure 4, all of the lateral forces at L₈, L₉, L₁₀ and L₁₁ act in the same direction so that clearances in the 55 trucks, etc., are all taken up in the same direction. (Those at the leading truck of unit No. 1 and the trailing truck of unit No. 3 are zero, or substantially so.)

60 It will be understood from the foregoing that two kinds of displacement between two adjacent vehicles must be 65 accommodated by the buffer mechanism. First, there is an equal and opposite angular displacement, when both vehicles are on the same curve, which displacement can be accommodated in mechanism having buffing-force transfer-points located on arcs centered on the truck centers, by forming the buffing surfaces in the shapes of 70 rockers or gear segments; and second, there is the unequal angular displacement of the end of one vehicle with respect to the adjacent end of another, which occurs when one vehicle is on a run of track having greater curvature 75 than the run of track on which the other vehicle is

located. That is also true when they are on trackage of opposite curvatures. It is accordingly necessary that the buffer mechanism permit such unequal displacement while at the same time providing an arcuate locus for the buffering-force transfer-point.

I have indicated in simplified form, in Figures 5 and 6, a buffering force transfer mechanism which meets these requirements. The buffer mechanism comprises spring loaded friction means generally indicated at 10, which means are secured to the end frames of the respective vehicles and which are provided with a toothed or corrugated member 11. The center of the teeth of member 11 lie on an arc 12, which arc has as its center the adjacent truck center pin 13. If it be assumed that the corrugated members 11 are in direct engagement with one another, it will be seen that, insofar as equal angular displacement of the two vehicles is concerned, the point of contact will always lie on the line 14 connecting the truck center pins.

However, as was pointed out above, it is necessary to accommodate unequal as well as equal angular displacement, and to that end, each buffer mechanism is provided with a buffer plate 15. Each buffer plate 15 is provided with a smooth surface 16 adapted to slidingly engage the corresponding surface of the buffer plate on an adjacent vehicle, and has developed on its opposite surface teeth or corrugations forming a rack adapted to cooperate with the teeth or corrugations of member 11. The centers of the corrugations on buffer plate 15, however, lie on a straight line 17.

With the mechanism illustrated in Figures 5 and 6, equal angular displacements between the two vehicles are accommodated by turning movement between members 11 and 15, and all unequal displacements are accommodated by sliding movement between adjacent members 15.

Since the buffering force is transmitted by members 11 and since the buffering force transmitting surfaces of members 11 all have the same effective distance from truck center pins 13, the forces transferred from one vehicle to another must lie on the line 14 connecting the truck center pins, with the result that no lateral forces are developed solely as a consequence of the separation between the buffering-force transfer-points and the truck center pins.

All of the foregoing discussion was concerned with the transmission from one vehicle to another of steady-state buffering forces, i. e., those forces incident to continued dynamic braking, continued pushing and the like. The vehicles, rails, draft gear and the like are all built to sustain such forces, and the features of the invention so far discussed have to do with the transfer of such forces from one vehicle to another.

However, railway operation also involves the development of forces of an entirely different character, i. e., instantaneous or transient forces arising out of slack take-up, coupling, and other operations in which the presence of inertia or momentum results in the application of forces much greater than the tractive effort or braking force developed by any locomotive. Draft forces of this character are absorbed by the draft gear and have no bearing on the present invention, but when one vehicle is suddenly accelerated toward another, buffering transients of very high peak magnitude may be developed, and it is necessary that the peak magnitude be limited to a value which will not damage the vehicle and, in the case of buffering forces having lateral components, to values which will not result in derailment and flange or rail breakage.

Conventionally, the problem presented by transient forces is solved in one or both of two ways, i. e., by transforming a portion of the kinetic energy of the transient into potential energy as by compressing or extending a resilient member, so that the transient is integrated over a finite period of time; or by transforming a portion of the mechanical energy into heat, as by friction means.

In the practice of the present invention, both means

are utilized and I prefer to employ a form of spring loaded friction damping means which is particularly well adapted for use in the buffer mechanism of the invention.

With these two functions established as criteria, the invention will now be described in terms of the specific embodiment illustrated in Figures 7 and 8.

The buffer mechanism of Figure 7 is enclosed in a supporting structure comprising back plate 20 (which is secured integrally, or by bolting or other suitable means—not shown—to the end frame of the vehicle), top plate 21 and bottom plate 22. A buffer plate 23 is connected to back plate 20 by means of spring assemblies 24, which constrain plate 23 against appreciable movement in the transverse and vertical planes, but which (as by loose pivot assemblies 24a and the yielding of the springs 24b) permit oscillatory movement of plate 23 about a vertical axis. Plate 23 is provided on its front surface with replaceable wear plates 25, welded thereto as at 25a; and on its opposite or rear surface with three corrugations or teeth 26 located with their centers along the dot-dash line 27.

Directly behind buffer plate 23 is located a toothed rocker or follower member 28, having teeth 29 formed with their centers on the arcuate line 30, which line is centered on the truck center pin. Rocker 28 is mounted for sliding movement between top and bottom plates 21 and 22 and side plates 31 and 32, which constrain it against lateral or vertical movement, but which permit reciprocation along the longitudinal center line of the vehicle.

Teeth 29 are adapted to engage teeth 26 of buffer plate 23 and to transfer buffering forces from buffer plate 23 to the vehicle frame.

Such forces are applied by rocker 28 to the vehicle frame through friction damping means comprising inclined surfaces 33 on rocker 28, wedges 34, springs 35—36, and wedge bearing plates 37.

In a typical example, springs 35 and 36 may be A. A. R. class "G" springs, types C and D respectively, with a maximum capacity of 30,360 lbs. with a $2\frac{1}{8}$ " total spring travel, and a capacity (both springs) of 28,200 lbs. after a 2" spring travel.

Each of the wedges 34 has a pair of inclined planes with a ratio of 1:2, so that the travel of each wedge 34 in the transverse direction is equal to the travel of member 28 in the longitudinal direction.

When a buffering force acts on buffer plate 23, it is transmitted to adjustable rocker 28, which presses against wedges 34 and causes them to move laterally against the pressure of springs 35—36. In the example mentioned, the total spring travel is 1", so that each wedge can move $\frac{1}{2}$ ". The spring force (for two springs) is thus 28,200 lbs. when the spring is compressed this distance of 1". In Figures 7 and 8, a starting clearance is shown between the parallel surface 38 of rocker member 28 and the confronting surface 39 of wedges 34, and a similar clearance between the corresponding bottom surfaces 40 and 41. In the example mentioned, this clearance is $\frac{7}{32}$ ". On application of a buffering force, the adjustable rocker can therefore move $\frac{1}{16}$ " in the longitudinal direction, during which time the wedges have moved $\frac{7}{32}$ " in the same direction, while each wedge moves $\frac{1}{16}$ " laterally, with the result that the spring is compressed $\frac{1}{8}$ ". When this condition has been reached, there is a gap of $\frac{1}{8}$ " between the confronting surfaces 42—43 of the two wedge members. But since the gap between surfaces 38 and 39 has been taken up, from this point onwardly only the wedge surface between the wedges 34 and the wedge bearing plates 37 will remain effective, with the result that during the last $\frac{1}{8}$ " of lateral travel of the wedges 34 ($\frac{1}{16}$ " travel of each wedge), rocker 28 will travel only $\frac{1}{32}$ " in the longitudinal direction. The total travel of the adjustable rocker 28, therefore, is $1\frac{15}{32}$ " before the buffer goes solid. During the first $\frac{1}{16}$ " of travel of the buffer, the following formula applies for each wedge:

In the practice of the present invention, both means

$$P = 2 \cdot W \cdot \tan(\alpha - \phi)$$

where P = spring force and W = buffing force.

The wedge ratio is 6 in 12, and $\tan \alpha = 0.5$, $\alpha = 26^\circ - 34'$. For a coefficient of friction of 0.3 = $\tan \phi$, ϕ equals $16^\circ - 42'$; $(\alpha - \phi) = 90 - 52'$ and $\tan(\alpha - \phi) = 0.1739$.

For $P = 26,050$ lbs. after a compression of $\frac{1}{8}$ "

$$W = \frac{26,050}{2 \times 0.1739} = 75,000 \text{ lbs.}$$

During the last $\frac{1}{32}$ " travel of the buffer, the following formula applies:

$$P = W \cdot \tan(\alpha - \phi)$$

For $P = 28,200$

$$W = \frac{28,200}{0.1739} = 162,000 \text{ lbs.}$$

Since there are two wedges the maximum buffing resistance of one buffer in the example mentioned is 324,000 lbs. Since it is contemplated that two such buffer mechanisms will be interposed between each two vehicles (one on the end of each vehicle), the total buffer travel will be $1\frac{5}{16}$ " before the buffers go solid.

Insofar as lateral forces are concerned, it will be clear (for the reasons set out in the discussion of Figures 5 and 6) that all buffing forces will be transmitted from one vehicle to another along the line connecting the truck centers, with the result that the peak lateral components of the buffing forces will be greatly reduced, as compared with conventional arrangements (in the ratios indicated in the diagrams of Figures 1 to 4, for the locomotive design, the buffing forces and the track curvature there given as examples).

As a practical matter, it is desirable to provide a clearance between the coupler pulling face and the face of the buffer plate 23, in order to permit easy coupling of two units equipped with couplers. The standard A. A. R. dimension for this clearance is $\frac{3}{8}$ ". It will be understood, therefore, that the draft gear will be compressed $\frac{3}{8}$ " before the buffer resistance becomes effective. As a consequence, there will be some compressive force in the draft gear, which force will have a small lateral component. However, according to the invention, the buffer resistance is made considerably higher than the draft gear resistance; and, when the buffers are in contact, they will transmit almost all of the buffing force, even on tangent track. When going around a curve, the clearance between the pulling face and the face of the buffer plate will become smaller and smaller according to the degree of curvature. For instance, when adjacent units are on a 13° curve, the clearance will be reduced by about $\frac{5}{32}$ ", according to the distance between truck centers and the pulling face, so that there is then only a slight draft gear resistance before the buffer becomes effective. If the curve becomes sharp enough, the draft gear will be placed in tension as soon as the buffer starts to compress. Under this condition, not only will the buffing force be transmitted exclusively through the buffers and hence along the line connecting the truck centers, but there will also be established an elastic system including the buffers and draft gear tending to restore the vehicles to aligned condition.

The relative resistance of the draft gear and buffers in a typical embodiment is diagrammatically indicated in Figure 13. Note that even on straight track, when the starting clearance is at a maximum ($\frac{3}{8}$ "), the draft gear resistance is relatively low, and, that once the buffer mechanism is engaged, by far the greater portion of the load is carried by the buffer. Note also that the rapid rise of buffer resistance in the last portion of its travel prevents travel of the draft gear into the region of its highest resistance.

The buffer mechanism illustrated in Figures 9 through 12 differs from the buffer mechanism of Figures 7 and 8 chiefly in that the buffer plate of this second form trans-

fers buffing forces to an adjacent vehicle through the diaphragm face plate.

In this construction, the buffer mechanism is secured to vehicle end frame 50 by welding thereto a buffer pocket comprising back plate 51, side plates 52-52, top plate 53 and bottom plate 54. Mounted in the pocket are springs 56 and 58, wedges 60, wedge bearing plates 62 and adjustable chafing plate or follower 64. Follower 64 is maintained in assembled position by means of bolts or pins 66 and is provided with teeth 68, generated on arcuate pitch line 70, adapted to engage with cooperating teeth 72 of buffer plate 74. Buffer plate 74 is maintained in assembled position by means of bolt or pin 76. Diaphragm plate 80 is mounted to vehicle frame 50 by diaphragm spring assemblies 82 which are secured to face plate 80 as at 84. Spring assemblies 82 (which may be in the form of spring-extended telescopic struts) are arranged to hold diaphragm face plate about $2\frac{5}{8}$ " beyond the coupling face when the vehicles are uncoupled, as indicated by the chain dotted outline 88.

Diaphragm plate 80 also carries diaphragm sill 86 which is pivotally secured to diaphragm 80 as at 88. The relationship between the buffer mechanism of the invention and coupler 90 is indicated in Figure 11. It will be observed that the buffing face of diaphragm face plate 80 is in the vertical plane of the coupler pull face 90a, but that plate 80 is slightly spaced from buffer plate 74 to provide the above mentioned standard coupling clearance.

In operation, buffing forces are transmitted through diaphragm face plate 80 to buffer plate 74, and thence to adjustable chafing plate or follower 64, longitudinal movement of which toward the vehicle causes lateral movement of wedges 60 and compression of springs 56, 58 in the manner described in connection with Figures 7 and 8. As in the first form of the invention described above, wedging action during the first part of the travel of follower 64 is effected both between the wedge surfaces 92 of follower 64 and the front surfaces of wedge 60, and also between the inclined surfaces of wedge bearing plates 62 and the rear surfaces of wedges 60. As in the case of the mechanism illustrated in Figures 7 and 8, however, the last portion of the inward movement of follower 64 is translated into lateral movement only by inter-engagement of the inclined surfaces of wedge bearing plates 62 and wedges 60, due to the closing of the gap between the surfaces 94-94 of follower 64 and the confronting surfaces 96-96 of wedges 60, as will appear most clearly from Figure 12. The effect of the closing of this gap on the operation of the buffer mechanism is illustrated in Figure 13 by the discontinuity in the curve of buffer resistance occurring at the $1\frac{5}{16}$ " point.

Thus, the buffer mechanism of the invention effects the transfer of buffing forces from one vehicle to an adjacent vehicle along the line connecting the truck centers, as a result of which no lateral forces on the trucks are developed solely as a result of the separation of the truck centers from the end of the vehicle. The elimination of such lateral forces eliminates the cause of jacking and consequent derailment and drastically reduces flange and rail wear.

The mechanism is compact and relatively light, and is accordingly easily embodied in new or existing equipment.

The presence of the buffer mechanism of the invention does not interfere with coupling operations.

Despite its relatively small size, my buffer mechanism is capable of absorbing transient buffing forces of very high peak magnitude with relatively little displacement of the buffer parts.

In the practice of my invention, I am enabled to retain relatively close spacing between the coupler pins of adjacent vehicles (which is a practical necessity in order to maintain the draft gear within reasonable limits as to length and thus avoid excessive encroachment there-

of on other parts of the vehicle when in action on curved track), while at the same time the buffing forces are transmitted through centers relatively farther apart, preferably at the truck centers (whereby the peak lateral components of the buffing forces are greatly reduced).

I claim:

1. Buffer mechanism for a railway vehicle having a truck connected to the vehicle by a truck pin located at a point removed from the end of said vehicle, said mechanism comprising a follower member mounted at the end of said vehicle for movement toward and away from said pin, means for opposing movement of said follower toward said pin, a buffer plate for transferring buffing loads between the buffer plate of another vehicle and said follower member, the surface of said buffer plate which engages the buffer plate of such other vehicle being configured to permit sliding contact therewith in a plane generally transverse the longitudinal axis of the vehicle, and the confronting faces of the buffer plate and follower being provided with inter-engaging means disposed on each side of said axis for transferring buffing forces therebetween and for preventing relative horizontal movement thereof transverse said axis, the inter-engaging means on said follower member being disposed at equal distances from said pin.

2. Buffer mechanism in accordance with claim 1 in which said inter-engaging means comprises a rack formed on said confronting face of said buffer plate and a segment of a pinion formed on said confronting face of said follower member, said segment having said pin for a center of curvature.

3. Buffer mechanism for a railway vehicle one end of which is supported by a truck whose center is spaced from the coupling face at said end, said mechanism comprising a buffer plate having a surface adapted to engage the corresponding surface of the buffer plate of an adjoining vehicle at said coupling face with freedom for relative sliding movement in a plane generally transverse the longitudinal axis of said vehicle to accommodate lateral displacement of said end of said vehicle relative to the end of said adjacent vehicle, means for mounting said plate on said vehicle with freedom for rocking movement about a vertical axis substantially coincident with the center of said truck, and means for confining lateral movement of said buffer plate relative to said vehicle to the rocking movement permitted by said mounting means.

4. Buffer mechanism for a railway vehicle, one end of which is supported by a truck whose center is spaced from the coupling face at said end, said mechanism comprising a buffer plate at the end of the vehicle having a surface adapted to engage the corresponding surface of the buffer plate of an adjoining vehicle with freedom for relative sliding movement in a plane generally transverse the longitudinal axis of said vehicle to accommodate lateral displacement of said end of said vehicle relative to the end of said adjacent vehicle, said buffer plate having a second surface generally parallel to said first surface, a follower member arranged to transmit buffing forces between said second surface of said plate and said vehicle, the surface of said follower member confronting said second surface being arcuate and having as its center said truck center, whereby to provide for rocking movement of said buffer plate relative to said vehicle to accommodate angular displacement of the end of said vehicle relative to the end of said adjacent vehicle, and inter-engaging teeth on the confronting surfaces of said buffer plate and rocker to prevent lateral sliding movement therebetween.

5. Buffer mechanism for a railway vehicle, one end of which is supported by a truck whose center is spaced from the end of the vehicle, said mechanism comprising means defining a buffer pocket at the end of the vehicle, a follower member mounted in said pocket with freedom for movement along the longitudinal axis of the vehicle toward and away from said center, means in said pocket for opposing movement of said follower toward said cen-

ter, a buffer plate extending generally transverse said axis adjacent the outer surface of said follower and adapted to transmit buffing force to the buffer plate of an adjacent vehicle, the confronting surfaces of said follower and plate being provided with inter-engaging teeth, the teeth of the buffer plate being generated on a straight pitch line to form a rack and the teeth of the follower member being generated on an arc, whose center is said truck center, to form a segment of a pinion.

10 6. Buffer mechanism for a railway vehicle, one end of which is supported by a truck whose center is spaced from the vehicle coupling face at said end, said mechanism comprising an adjustable chafing plate for transmitting buffing forces having a force-transmitting surface defined by an arc struck from said truck center, a buffer plate for transmitting buffing forces between said chafing plate and the buffer plate of an adjacent vehicle, said buffer plate having a first surface adapted to engage said corresponding buffer plate with freedom for sliding movement in a plane generally transverse the vehicle axis, and having a second surface parallel to the first in engagement with said arcuate surface, and means for confining relative movement between said buffer plate and chafing plate to rocking movement about said center.

25 7. Buffer mechanism for a railway vehicle, one end of which is supported by a truck whose center is spaced from the coupling face at said end, which mechanism comprises means defining a buffer pocket at said end of the vehicle, an adjustable chafing plate in said pocket having freedom for movement toward and away from said center, spring and wedge means in said pocket for opposing movement of said chafing plate toward said center, a chafing surface on said chafing plate comprising teeth generated on a pitch line which is an arc of a circle centered on the truck center, a buffer plate for transmitting buffing forces between said chafing plate and the buffer plate of an adjacent vehicle, said buffer plate having a first generally plane surface adapted to engage another buffer plate with freedom for sliding movement in a plane generally transverse said axis and a second surface generally parallel to the first and having thereon teeth generated along a straight pitch line and adapted to inter-engage with the teeth of said chafing plate.

40 8. Buffer mechanism comprising wedge means movable transverse the axis of buff, resilient means for opposing movement of the wedge means in one direction, said wedge means having two opposed wedge surfaces inclined toward one another in a direction opposite said first direction, wedge bearing means having an inclined surface parallel to and engageable with one of said wedge surfaces, buffing-force-transmitting means movable under buff along said axis toward said bearing means from an unloaded to a loaded position and having an inclined surface parallel to and engageable with the second of said wedge surfaces, whereby buffing movement of said transmitting means urges said wedge means in said one direction against the opposition of said resilient means, stop means on said wedge means comprising a first stop surface extending transverse the axis of buff, and stop engaging means on said transmitting means comprising a second stop surface parallel to said first stop surface, said first and second stop surfaces being relatively positioned to abut one another upon movement of said transmitting means to a point intermediate its loaded and unloaded positions.

45 9. Mechanism for transmitting buffing forces from one railway vehicle to another, comprising, at an end of such a vehicle, a follower member mounted for longitudinal movement relative to the vehicle, a plate member adapted to transmit buffing forces between said follower member and the plate member of an adjacent vehicle, said follower and plate members having vertical confronting surfaces, one of which is arcuate, whereby to provide for rocking of one member on the other to accommodate relative angular displacement of one vehicle with respect to

the other, means for opposing longitudinal movement of said follower member in buff, comprising wedge means movable transverse said axis, resilient means for opposing movement of said wedge means in one direction, said wedge means having opposed wedge surfaces inclined toward one another in a direction opposite said one direction, and fixed wedge bearing means engaging one of said wedge surfaces, the other of said wedge surfaces being in engagement with a corresponding surface developed on said follower member, whereby movement of said follower member toward said bearing means responsive to a buffing force is translated into movement of said wedge means, in said one direction against the opposition of said resilient means.

10. Mechanism for transmitting buffing forces from one railway vehicle to another, comprising, at an end of such a vehicle, a follower member mounted for longitudinal movement relative to the vehicle, a plate member adapted to transmit buffing forces between said follower member and the plate member of an adjacent vehicle, said follower and plate members having vertical confronting surfaces, one of which is arcuate, whereby to provide for rocking of one member on the other to accommodate relative angular displacement of one vehicle with respect to the other, means for opposing longitudinal movement of said follower member in buff comprising wedge means movable transverse said axis, means

for opposing movement of said wedge means in one direction, said wedge means having opposed wedge surfaces inclined toward one another in a direction opposite said one direction, fixed wedge bearing means engaging one of said wedge surfaces, the other of said wedge surfaces being in engagement with a corresponding surface developed on said follower, whereby movement of said follower toward said bearing means responsive to a buffing force is translated into movement of said wedge means in said one direction against the opposition of said resilient means, and stop means on said wedge means comprising a first stop surface extending normal to the said axis, and a second stop surface on said follower member disposed parallel to said first stop surface and positioned relative thereto to engage said first stop surface in an intermediate position of movement of said follower toward said wedge bearing means.
